UNITED STATES PATENT OFFICE.

JOHN B. CAMERON, OF LAWRENCE, MASSACHUSETTS.

BENDING-MACHINE.

No. 905,841.

Specification of Letters Patent.

Patented Dec. 8, 1908.

Application filed June 11, 1907. Serial No. 378,433.

To all whom it may concern:

Be it known that I, JOHN B. CAMERON, a citizen of the United States, residing at Lawrence, in the county of Essex and State of Massachusetts, have invented a new and useful Improvement in Bending-Machines, of which the following is a specification.

This invention relates to bending machines, and more particularly to wood bending machines, especially adapted for bending shafts, the object being to provide a machine which will bend the shaft without any danger of breaking or cracking the same.

Another object of my invention is to provide a machine which can be readily operated by one man and one which is constructed that it can be adjusted so as to bend the shaft any shape desired.

Another object of my invention is to provide a machine which is very simple and cheap in construction, and one which is very strong and durable.

With these and other objects in view, the invention consists in the novel features of construction, combination and arrangement of parts, hereinafter fully described and pointed out in the claims.

In the drawings forming a part of this specification:—Figure 1 is a side elevational view of my improved bending machine showing a shaft in dotted lines arranged therein being bent into the proper shape. Fig. 2 is a sectional view taken on line 2—2 of Fig. 1. Fig. 3 is a section taken on the line 3—3 of Fig. 1. Fig. 4 is a section taken on line 4—4 of Fig. 2. Fig. 5 is a section taken on line 5—5 of Fig. 1, and Fig. 6 is a detail top plan view of the frame carrying the guide.

In the drawings A indicates a post secured to the floor by angled plates A' over which is secured about midway of its height one end of a rectangular frame B, the outer end of which is secured over a post C secured to the floor by an angled plate C', it of course being understood that any suitable supporting means desired can be used.

Mounted in bearings arranged in the side bars of the frame B, adjacent its outer end is a shaft D provided with a crank handle D' at one end by means of which the shaft is rotated. Fixed on the shaft in the frame adjacent one side bar is a gear-wheel D² which meshes with a gear-wheel E' secured on a shaft E mounted in bearings in the side bars of the frame. The shaft extends out through

one side bar of the frame, on which is secured a gear-wheel E² which meshes with a gear-wheel F' loosely mounted on one end of a shaft F secured in the side bars of the frame, adjacent the post A.

Secured on the side of the post A from which the frame B extends, are spaced plates G provided with enlarged apertured ends G', in which are secured the ends of guide-rods G², on which are slidably mounted blocks H' carrying a shaft H which extends out over the gear wheel F' and on which is mounted a pressing roller J. The plates are also provided with central apertured enlargements G³ in which is mounted the reduced ends of an adjusting screw I, on which is mounted a threaded block H² carried by the shaft H. A hand-wheel I' is secured on the upper end of the screw, so that by rotating the screw, the shaft carrying the pressing roller can be adjusted up and down as desired.

The apertured ends of the frame K are secured on the shaft H by set-screws and are provided with outwardly extending apertured arms K' in which is secured a shaft K² on which are adjustably mounted guide-arms K³ by set-screws, so that the guides can be adjusted to suit different width shafts as will be hereinafter fully described.

Detachably mounted on the end of the shaft F is a block L provided with apertured ears through which extend the parallel side bars of a U-shaped frame L', the ends of the bars being connected together by a plate L² secured in place by nuts and provided with a central threaded bore, in which is mounted a threaded screw L³ the lower end of which is swiveled in a block L⁴ which is mounted on the shaft H and is provided with apertured ears, through which the side bars of the frame L' extend. A hand-wheel L⁵ is secured on the upper end of the screw, so that the frame can be adjusted, so as to support the end of the shaft F and relieve it of the great strain it is subject to when a wagon shaft is being bent.

Pivotedly mounted on the ends of the shaft F adjacent the side bars of the frame B are the apertured ends of the U-shaped frame M provided with bearings adjacent its outer end, in which is mounted a shaft M', on one end of which adjacent one side bar, is mounted the apertured end of a curved arm M² which works through a guide

N secured to the side of the post A, and is provided with a series of openings, in which is secured a pin M³ forming a stop to limit the downward movement of the frame, which will be hereinafter fully described. A spring actuated block N' is mounted in the bottom of the guide N adapted to force the notch M⁴ of the curved arm against the top of the guide, so as to hold the frame up in position. Bearings are formed in the side bars of the frame, in which is mounted the shaft O, on which is fixed a gear-wheel O' meshing with the gear-wheel F' so that when the crank is turned, the gear wheel O' will be operated.

Secured on the outside of the gear-wheel F' by bolts P' is a cylindrical mold P which can be readily detached when desired. A similar mold Q of a less diameter is secured to the outer face of the gear wheel O' by bolts Q', on one of which is secured a clamping iron Q² adapted to engage the end of the shaft when forced into the machine between the mold P and pressing roller J. A tripping member R is clamped over the periphery of the gear O' provided with a finger R' adapted to engage a curved arm M² and force the notch out of the guide so that the frame can swing downwardly.

The operation for bending the rear end of the shaft is as follows: The frame M is raised up until the notch in the arm M² catches in the guide, which holds the frame securely in position, bringing the periphery of the mold Q in alinement with the periphery of the roller, and the clamping member in alinement with the mold P. The shaft to be bent which has been previously steamed is shoved into the machine between the guides and mold, and the end clamped between the clamp Q² and mold Q. The crank arm is then turned which rotates the gear-wheels F', O' carrying the molds P and Q until the tripping finger carried by the gear O' engages the curved arm which forces the notch out of the guide, and releases the frame. When the wheel reaches this position it is prevented from rotating any further by the finger, and as the gear F' continues to rotate, the gear-wheel O' will be drawn downwardly until the pin which has been set in the arm engages the guide and regulates the amount of bend to the shaft. The shaft is then drawn out and placed in suitable form until it hardens.

Having thus fully described my invention, what I claim as new and desire to secure by Letters Patent is:—

1. In a bending machine, the combination with a gear-wheel, a mold secured on said gear-wheel, of a swinging frame, a gear-wheel carried by said frame meshing with said gear-wheel, a mold secured on the gear-wheel carried by the frame, and means for rotating the first mentioned gear-wheel whereby the gear

carried by the frame will be rotated and the frame swung on its pivot.

2. In a bending machine, the combination with a rotary mold, of a swinging frame, a rotary mold secured on said gear wheel 70 geared to the first mentioned mold, whereby the last mentioned mold will be rotated and the frame swung downwardly when the first mentioned mold is operated.

3. In a bending machine, the combination 75 with a rotary mold, of a swinging frame carrying a rotary mold, geared to the first mentioned mold, means for supporting said frame and means for releasing said frame, rotating said molds and swinging said frame. 80

4. In a bending machine, the combination with a frame, of a mold revolvably mounted on said frame, a spring actuated pressing roller mounted above said mold, a frame pivotally mounted on the first mentioned frame, 85 a rotary mold mounted on the pivoted frame geared to the mold, of the fixed frame whereby the frame will be swung and the mold rotated when the first mentioned mold is operated.

5. In a bending machine, the combination with a frame, of a mold revolvably mounted on said frame, a pressing roller mounted above said mold, a frame pivoted to the fixed frame, a mold revolvably mounted on the 95 fixed frame, and a clamping member carried by the mold carried by the pivoted frame.

6. In a bending machine, the combination with a frame, of a mold revolvably mounted on said frame, a pressing roller mounted above said roll, a frame pivoted to said fixed frame, a mold revolvably mounted on the pivoted frame, and a clamping member carried by the mold mounted on the pivoted frame.

7. In a bending machine the combination 105 with a fixed frame of a cylindrical mold mounted on said fixed frame, a frame pivotally mounted on the first frame, a cylindrical mold mounted on said pivoted frame, an arm carried by the pivoted frame, means carried 110 by the fixed frame for locking said arm, and means carried by the mold of the pivoted frame for tripping said locking means.

8. In a bending machine, the combination with a post carrying a fixed frame, of a shaft 115 secured on said fixed frame carrying a gear, a mold secured to said gear, a frame pivotally mounted on said shaft, a shaft secured in the pivoted frame carrying a gear meshing with the gear of the fixed frame, a mold carried 120 by the gear of the pivoted frame, an arm carried by the pivoted frame and working through the guide secured on said post, and a tripping finger carried by the gear mounted on the pivoted frame adapted to engage said 125 arm for the purpose described.

9. The combination with a post, of a frame secured on said post, a shaft secured in said frame, a gear mounted on said shaft, a cylindrical mold secured to said gear, a 130

pressing roller adjustably mounted above said mold, a frame pivotally mounted on said shaft, a shaft secured in the pivoted frame, a gear mounted on the last mentioned shaft meshing with the first mentioned gear, a mold secured to said gear carried by the pivoted frame, a clamping member, secured to the last mentioned mold, a guide secured to said post provided with a spring actuated 5 block, a notched curved arm carried by the pivoted frame, working through said guide, and a tripping member carried by the gear

mounted on the pivoted frame adapted to engage said arm.

10. In a bending machine, the combination with a rotary mold, of a pivoted frame carrying a rotary mold geared to said mold, and a clamping member carried by the mold carried by the pivoted frame.
